UNITED STATES PATENT OFFICE.

TAKANOSHIN DOMOTO, OF SAN FRANCISCO, CALIFORNIA.

CAN-LINING.

1,020,134.

Specification of Letters Patent.

Patented Mar. 12, 1912.

Application filed November 15, 1911. Serial No. 660,416.

To all whom it may concern:

Be it known that I, TAKANOSHIN DOMOTO, a subject of the Emperor of Japan, residing at the city and county of San Francisco and 5 State of California, have invented new and useful Improvements in Can-Linings, of which the following is a specification.

This invention relates to envelops or wrappers for material to be preserved in 10 cans.

The object of the present invention is to provide and employ a wrapper or envelop for the protection of material to be preserved in cans against deterioration and 15 discoloration.

A particular object of the present invention is to provide for such an envelop or wrapper a material which is both clean, durable and has certain properties which 20 effectually protect the contents of the can from staining or other injuries due to contact with the inner surface of the latter.

The invention consists of the parts and the construction and combination of parts, 25 as hereinafter more fully described and claimed, having reference to the accompanying drawings, in which—

Figure 1 is a perspective view of the can broken away indicating the contents as enveloped in the wrapper. Fig. 2 is a perspective view of the wrapper.

I have discovered that the contents or materials placed in cans for their preservation may be protected from staining, discoloration and other injurious effects by 35 their contact with the interior of the can, by enveloping them in a sheath or wrapper made of a fibrous, natural and unprepared material, and particularly I have found that 40 these wrappers can be inexpensively and satisfactorily produced by the use of dried leaves 2 of bamboo. These leaves are of

considerable area and can be obtained readily, measuring up to approximately 6 inches in width and 18 inches in length, thus one 45 leaf of bamboo affords ample material for the wrapping of a volume of substance to be preserved.

The natural properties of bamboo leaves render them valuable for the envelopment 50 of the goods to be preserved in cans 3 or other containers, and I have found that a bamboo wrapper effectually prevents the access of moisture from the goods to be preserved to the can and vice versa, and that 55 the qualities of the bamboo leaf are such as to prevent the staining of the goods, thus rendering this particular kind of wrapper extremely valuable.

The leaves may be first subjected to any 60 desired cleansing and smoothing process, and then cut to fit the interior size and shape of the can, so as to practically form a lining between the sides and the contents of the can. Separate forms may be cut to 65 fit the bottom and top of the can and thus practically complete the lining.

Having thus described my invention, what I claim and desire to secure by Letters Patent is—

The improvement in separating containers from the contents thereof, consisting in applying independent removable lining within the container, formed of bamboo leaves prepared and shaped to fit the interior of the container.

In testimony whereof I have hereunto set my hand in the presence of two subscribing witnesses.

TAKANOSHIN DOMOTO.
